CLAIM

The ornamental design for a power adapter for computer and
USB hub, as shown.

DESCRIPTION

FIG. 1 is a top plan view of the power adapter for computer
and USB hub of the present invention;

FIG. 2 is a bottom plan view thereof;

FIG. 3 is a left side elevation view thereof;

FIG. 4 is a right side elevation view thereof;

FIG. 5 is a rear elevation view thereof; and,

FIG. 6 is a front elevation view thereof.
